UNITED STATES PATENT OFFICE.

FREDERICK HAROLD CRITCHLEY, OF LIVERPOOL, ENGLAND.

ARTIFICIAL LIMB.

1,283,093.

Specification of Letters Patent. Patented Oct. 29, 1918.

Application filed June 13, 1918. Serial No. 239,773.

To all whom it may concern:

Be it known that I, FREDERICK HAROLD CRITCHLEY, a subject of the King of Great Britain, and a resident of Liverpool, England, have invented certain new and useful Improvements in Artificial Limbs, of which the following is a specification.

This invention relates to improvements in artificial limbs and is particularly directed to the manufacture of artificial legs. The great disadvantage in the present construction of artificial legs arises from the fact that the knee-joint while limited against rearward closing movement is quite free to close by forward movement, and consequently should the weight of the wearer be thrown on the leg when the knee-joint is in a flexed position, a collapse of the artificial limb is inevitable, and where provision has been made to obviate this, such as by fitting pieces of elastic material, it is not satisfactory, the elastic material being insufficient to prevent collapse of the joint under the weight of the wearer. In the action of walking, however, when the artificial limb is thrown forward the knee-joint should be slightly flexed and provision should be made for preventing the forward collapse of the limb when the weight of the wearer comes on the knee-joint and the object of the present invention is to provide means to insure this.

An artificial leg in accordance with this invention is shown in the accompanying drawings, in which Figure 1 is an elevation partly in section, showing the leg slightly flexed at the knee-joint, Fig. 2 being a fragmentary detail showing the knee-joint pivot in outside view, Fig. 3 a cross section through the knee portion of the leg showing the joint in end view, and Fig. 4 a perspective view of the detachable rubber toe piece for the foot. Fig. 5 is an outside view of the leg corresponding to Fig. 1, Fig. 6 being a section on an enlarged scale of the knee joint pivot and Fig. 7 a cross section of this pivot in a plane at right angles to Fig. 6.

In carrying out the invention, a skeleton framework of metal is built up consisting of a lower tubular or like element 1 in the calf portion of the leg pivotally connected at the

knee to straps or the like pieces 2 in the thigh part of the leg. The tubular element 1 is pivotally connected at 3 to the foot piece 4, say, by means of looped rods 5 passing around grooved rollers 6. The knee joint is formed in the manner of a barrel 7 carried from and held against rotation by the straps 2 and adapted to be frictionally gripped by a band brake, the band 8 of which, while normally loose when the weight of the wearer is not on the limb is adapted to be tightened about the barrel 7 by the downward pull of a rod 9 pivotally connected at 10 to the heel part of the foot piece 4, the upper end of the rod passing through split lugs 11 on the band 8, a nut 12, when the rod 9 is drawn down, contracting the band 8 about the barrel, so preventing relative rotary movement between the band and the barrel locking the joint. The band 8 is rigidly fixed and carried at the top of the tube 1, and the barrel being carried by the straps 2, the arrangement forms an easy pivotal joint offering a large wearing surface. The foot piece 4 being pivoted to the tubular element 1 at 3, when the weight of the wearer is thrown on the toe of the foot piece the latter tends to turn about the pivot 3, drawing down the rod 9 which, by pressing on the upper lug 11 contracts the band 8 on the barrel 7 and locks the joint. In this way no matter what the flexion of the knee joint forwardly, the leg as a whole cannot collapse about this joint even though it carries the full weight of the wearer. When the leg is lifted, the knee joint will, however, again become loose, and the lower part of the leg free to swing. The band 8 normally tends to open and free itself by its own resilience, the lugs 11 being then slightly open, and if desired a compression spring 13 may be fitted bearing against a collar 14 on the rod 9 and the head of a sleeve 15 on the rod adapted to take the thrust of the spring against the lower lug 11. The function of this spring 13 is to keep the nut 12 in close contact with the upper lug 11, thus preventing any knock or jar when the pull comes on the rod 9, the action of such spring 13, however, not being strong enough to lock the knee joint. In this way the knee joint is normally loose as the leg is

thrown forward in the action of walking and when not bearing the weight of the wearer, but directly the foot piece bends about the ankle pivot 3 due to the weight of the wearer coming on the leg the knee joint is immediately safely locked. A pin 16, Fig. 6, is provided in the strap 8 which acts to limit the angular swing of the calf piece of the leg, and in order that this pin should not 10 make any noise or jar, stops are formed by rubber rods 19 fitted into sockets 20 in the barrel 7, and a slot 21 is formed in the barrel through which the pin 16 projects, the pin traveling in the slot as the band 8 rotates. The slot 21 is carried halfway through the sockets 20 so as to leave the rubber rods 19 exposed for contact with the pin 16 as the lower part of the leg swings angularly to its limits. The barrel 7 is inclosed 15 by a spigoted cap 22, and the straps 2 of the thigh piece are socketed to the barrel 7 and its cap 22 within ribs 23, the pivotal bolt 24 and the inner side cheeks of the thigh piece 25 holding the straps in engagement. The 20 tubular element 1 and the straps 2 carry the molded limb portions *a*, *b*, of the calf and thigh, respectively, which limb portions, as they do not carry any of the weight of the wearer, may be made out of light sheet 25 metal, papier mâché, or wood or molded out 30 of suitable material, and may be made extremely light with a resulting advantage in the total weight of the limb. A detachable toe piece, Fig. 4, is provided of rubber, this 35 toe piece 26 having a spigot 27, which is entered into a corresponding socket in the foot piece 4, a sole 28 passing beneath the foot piece and the heel projection 29 entering into a socket, so that by attaching the heel 40 by a screw 30 the whole toe piece is retained in place.

The strap pieces 2, as shown in Fig. 3, are bent outward and brought on the outside of the bucket part of the thigh piece, and they 45 may be braced at their upper ends by a rear metallic strap 31. The leg may be attached to the wearer in any suitable or known manner, such as by the buckles 32 connecting up to any form of braced suspension, or otherwise, and the bucket is fitted with the usual 50 lacing 33. The calf may be built in two parts about the tubular element 1 doweled at 33 and held together by a bolt 34, the calf parts *a* being supported from the element 1 55 by pins 35.

With such a construction besides the advantage that the leg though flexed becomes rigid when supporting the weight of the wearer; owing to the fact that the weight 60 is carried by a metallic framework and not by the material of which the leg is shaped, the metallic framework and the molded or otherwise formed leg portions may be stand-

ardized, and the articulated metal framework made by different workmen than those 65 engaged in shaping the contoured limb parts.

I claim:—

1. In an artificial limb, a thigh piece, a calf piece, a knee joint coupling the thigh and calf pieces and normally loose, and a 70 pivoted foot piece, a connection between the foot piece and knee joint whereby the pivotal movement of the foot piece coacts to lock the knee joint against flexure.

2. In an artificial limb, a thigh piece, a 75 calf piece, a knee joint comprising a barrel element carried from one part of the limb co-acting with a brake band carried from the other part of the limb, said band being normally loose about the barrel, but contractible thereon to lock the joint when weight or end thrust is thrown on the limb. 80

3. In an artificial limb, a thigh piece, a calf piece, a knee joint comprising a barrel element carried from one part of the limb 85 co-acting with a brake band carried from the other part of the limb, said band being normally loose about the barrel, and a pivoted foot piece, a connection between the foot piece and knee joint whereby the pivotal movement of the foot piece coacts to contract the band on the barrel and lock the knee joint against flexure. 90

4. In an artificial limb, a thigh piece, a calf piece, a knee joint comprising a barrel 95 element carried from one part of the limb co-acting with a brake band carried from the other part of the limb, said band being normally loose about the barrel, a pivoted foot piece, and a pull rod connected to the 100 heel of the foot piece engaging the band, pivotal movement of the foot piece acting to contract the band on the barrel and lock the knee joint against flexure.

5. In an artificial limb, a thigh piece, a 105 calf piece, a knee joint comprising a barrel element carried from one part of the limb co-acting with a brake band carried from the other part of the limb, said band being normally loose about the barrel, a pivoted 110 foot piece, a pull rod connected to the heel of the foot piece engaging the band, and a spring keeping the pull rod in close engagement with the band, pivotal movement of the foot piece acting to contract the band 115 on the barrel and lock the knee joint against flexure.

6. In an artificial limb, a thigh piece, a calf piece, a knee joint comprising a barrel element carried from one part of the limb 120 co-acting with a brake band carried from the other part of the limb, said band being normally loose about the barrel, a pin projecting from the band traversing a slot in the barrel, a cushion abutment at each end 125 of the slot adapted to silence the impact of

the pin, and a pivoted foot piece, pivotal movement of the foot piece acting to contract the band on the barrel and lock the knee joint against flexure.

5 7. In an artificial limb, a skeleton framework by means of which the various parts of the limb are articulated together and which takes the weight of the wearer, and molded or shaped limb pieces which do not

take the weight of the wearer but are merely attached to and supported from the framework.

In testimony whereof I affix my signature in presence of two witnesses.

FREDERICK HAROLD CRITCHLEY.
